UNITED STATES PATENT OFFICE.

CLIFTON B. CORELL, OF NEW YORK, N. Y., ASSIGNOR TO UNDERWOOD COMPUTING
MACHINE COMPANY, OF NEW YORK, N. Y., A CORPORATION OF NEW YORK.

TYPE-WRITING MACHINE.

1,262,310.

Specification of Letters Patent.

Patented Apr. 9, 1918.

Application filed August 30, 1916. Serial No. 117,575.

To all whom it may concern:

Be it known that I, CLIFTON B. CORELL, a citizen of the United States, residing in New York city, in the county of New York and State of New York, have invented certain new and useful Improvements in Type-Writing Machines, of which the following is a specification.

This invention relates to sheet collating devices for typewriting machines of the class in which sheet impaling pins or studs are provided to be projected through perforations in the side margins of work sheets arranged on a collating table, for alining the sheets or holding them in adjustable position. The studs may be withdrawn from the work sheets after the latter have been adjusted, to permit the sheets to be advanced over the platen of the typewriting machine. As the impaling pins may be made to fit snugly in the openings in the sheets to obtain a positive and exact alinement, it is important that the pins should be withdrawn by a straight line movement perpendicular to the sheets in order to prevent tearing of the sheets or displacement of the latter as the pins are withdrawn.

An object of the present invention, is to provide improved means for withdrawing the impaling pins in the manner stated. In practising the invention the sheet collating table, which may be located at the delivery side of the platen to extend upwardly and rearwardly beyond the printing line, may be provided with a row or rows of impaling pins arranged to enter rows of openings provided along the side margins of the work sheets. In order to support the pins and permit them to be withdrawn in a direction normal to the work sheets, each row of pins may be carried on a shiftable support located behind the table, with the pins projecting through openings in the table, which openings may serve to position and guide the pins. Said supports may be actuated by cams to project or withdraw the pins. The cams may be in the form of inclined slots in actuating devices, mounted to slide on the rear face of the table, the slots arranged to receive studs on said supports so that the sliding movement of the actuating devices may serve to shift the supports toward and from the table to project and withdraw the impaling pins. The actuating devices may be operated by a key connected thereto

through suitable mechanism, as for example, a rock shaft carrying the key, pinions on said shaft, and racks on the actuators driven by the pinions.

Other features and advantages will appear hereinafter.

In the accompanying drawings,

Figure 1 is a front perspective view of the carriage of an Underwood typewriting machine with the present invention applied thereto.

Fig. 2 is a rear perspective view of the sheet collating table, and also shows the mechanism for withdrawing the impaling pins.

Fig. 3 is a sectional elevation of the platen frame and collating table, the impaling pins being shown in operative position.

Fig. 4 is a similar view, but with the pins withdrawn.

Fig. 5 is a view showing certain of the parts separated or before they are assembled, particularly the table, a pin-carrying support, and the actuating means for shifting said support.

The roller platen 10 is mounted on a platen axle 11, journaled in the ends 12 and 13 of the platen frame, which also comprises an inclined paper-shelf 14 at the intake side of the platen. Type-bars 15 (Fig. 4) may be operated by the usual mechanism to cause the types thereon to print at the front face of the platen. Front and rear feed rolls 16 and 17 bear against the under side of the platen and cooperate therewith to feed the work-sheets around the lower side of the platen and upwardly past the printing line. The feed-roll shafts are mounted on levers 18, journaled on a rod 19, said levers being actuated by a rock shaft 20 having cams or flats operative when said shaft is rocked to spread the arms 21 of said levers, and thereby throw the feed rolls off the platen. A feed-roll release key 22 is connected through a link 23 to a rock arm 24 on the shaft 20, whereby, when said key is depressed, the shaft 20 is rocked and the rolls 16 and 17 are moved downwardly away from the platen. The feed rolls are restored to the platen by springs (not shown) when an upward pressure is applied to the key 22.

The platen may be rotated either by the hand-wheels 25 on the platen axle, or by the usual line-spacing mechanism. The latter comprises a line-spacing lever 26 operable to

move rearwardly a slide bar 27 carrying a pawl to drive a line-space ratchet wheel 28 connected with the platen.

The above described parts may be of the usual construction, common in commercial Underwood typewriting machines.

The sheet collating table 30, may comprise end sections 31 and 32 and an intermediate connecting plate 33. The end plates 31 and 32 are adjustably connected to the plate 33 by means of screws 34 extending through elongated slots 35 in said end plates and clamping the latter to the plate 33. By loosening the screws, the ends 31, 32 may be 10 adjusted lengthwise of the plate 33 to adjust impaling pins or studs 36 for sheets of different widths, or for adjusting the position of a sheet held by one row of pins relative to that of a sheet held by the other row 15 of pins. The collating table 30 is mounted on the platen frame in position to extend upwardly and rearwardly from the platen so that work sheets *a*, *b*, on the platen may have their leading ends overlie the table 30, 20 permitting the sheets to be arranged and alined on the impaling studs 36. Means for mounting said table, comprises brackets 37 on the platen ends, a tie rod 38, connecting said brackets, and a rod 39 extending between the platen frame ends. Brackets 40, 25 supported on the rods 38 and 39 have forwardly extending arms 41 secured to the sheet collating table, as by means of clamping screws 42 extending through vertical slots 43 in the ends 31 and 32, and threaded into the bracket arms 41. This connection permits adjustment of the table toward and from the platen, the screws 42 clamping the table in adjusted position on the said brackets 40.

The impaling studs 36 are arranged in rows adjacent the ends of the table 30, each row of studs being carried by a support 44 behind the table so that the studs extend 45 through openings 45 in the table and project above the surface of the table and perpendicular thereto. The supports 44 are shiftable toward and from the table to project and withdraw the studs, by means of 50 actuators 46 having cam slots 47 to receive headed pins 48 extending through said cam slots and secured to the supports 44.

The actuators 46 are mounted on the rear face of the table for sliding movement thereon, toward and from the platen; such mounting comprises headed pins 50 extending through longitudinal slots 51 on the bottom or rear wall of the actuator into guide blocks 52 secured to and projecting 55 rearwardly from the collating table near the upper end thereof. The lower ends of the actuators 46, are in like manner guided and supported by pins 54 extending through slots 55 in the actuator, said pins 54 being mounted on angle plates 56 attached by

screws or bolts 57 to an angle bar 58, secured to and extending lengthwise of the table along the bottom edge thereof. With this construction, the actuators 46 are permitted to slide up and down on the table but 70 are held against either lateral movement or movement toward and from the table.

Means for operating the actuators 46 comprises a key 60 on a rock shaft 61 to which are fixed pinions 62 running in mesh 75 with racks 63 on actuators 46. The rock shaft 61 is mounted at the back of the collating table, being journaled in bearing blocks 64, secured to the rear face of the plate 33.

When the key 60 is thrown upward to the position shown in Figs. 1 and 3, the pin-carrying supports 44 are held closely against the rear face of the table so that the pins 36 project through the openings 45 into 85 position to permit the arrangement of the work sheets thereon. To withdraw said pins, the key 60 is swung downward to the Fig. 4 position, thereby rotating the pinions 62 and operating the racks 63 so that the 90 actuators 46 are slid upwardly or away from the platen. By this movement, the cams 47 sliding along the pins 48 move the latter rearwardly, that is to say, the carriers 44 are moved away from the table in a direction perpendicular thereto, thus withdrawing the pins 36 from the work sheet.

It will be seen that the supports 44, owing to the pins 36 being held and guided in the openings 45 in the table, are only moved in 100 a direction perpendicular to the table. The pins 36 are thus withdrawn without tearing or displacing the sheets.

To permit the arrangement of the work sheets, the feed rolls 16 and 17 may be 105 thrown off the platen by depressing the key 22. The first sheet *b* may then be dropped on the paper shelf 14 and advanced around the under surface of the platen to bring the leading end of the sheet over the collating 110 table 30. The sheet, by means of the perforations in its side margin may then be impaled on the projecting studs 36 whereby the sheet is alined and squared to the platen in position to receive the first line of typewriting. An outer sheet *a* with an intermediate carbon sheet may then be introduced between the first sheet *b* and the paper shelf 115 14 and advanced to position to be written upon, the sheet being adjusted on the studs 36 and thus alined in the same manner as the first sheet. The sheets as thus arranged may have their leading ends at different positions of advancement depending on the character of the sheets and the position at 120 which the typewritten entries are to be made on the several sheets. The sheets being thus arranged, the key 22 is lifted to return the feed rolls 16 and 17 for holding the sheets to the platen in their relative posi- 125 130

tion of adjustment. The key 60 is now thrown down to withdraw the studs 36 so that the sheets may be advanced over the collating table without interference from 5 said pins as the platen is rotated.

Variations may be resorted to within the scope of the invention, and portions of the improvements may be used without others.

Having thus described my invention, I 10 claim:

1. The combination with a sheet supporting table, of a series of pins arranged to project beyond the surface of the table to enter perforations in a work sheet on the 15 table, a support on which said pins are mounted, an actuator mounted on the table for movement in a direction parallel with the sheet supporting surface, and means for causing said movement of the actuator to move said support in a direction perpendicular to said surface of the table to move the pins toward or from effective position.

2. The combination with a sheet supporting table, of a series of pins arranged to project beyond the surface of the table to enter perforations in a work sheet on the table, a support on which said pins are mounted, an actuator mounted on the table for movement in a direction parallel with the sheet supporting surface, and cams operated by said actuator to move said support toward and from the table for projecting and retracting the impaling pins.

3. The combination with a sheet supporting table, of a series of pins arranged to project beyond the surface of the table to enter perforations in a work sheet on the table, a support on which said pins are mounted, an actuator mounted on the table 40 for movement in a direction parallel with the sheet supporting surface, said actuator having inclined cam slots, and studs on said support to work in said slots whereby said movement of the actuator is effective to move the support toward and from said table to project and withdraw the impaling pins.

4. The combination with a sheet supporting table, of a series of impaling pins, a support behind the table on which said pins are carried, said support movable toward and from the table to project and withdraw said pins to and from position to enter perforations in a work sheet supported on the 55 table, an actuator mounted to slide on the table, and means whereby said movement of the actuator is transmitted to the support for

moving the latter toward and from the table.

5. The combination with a sheet supporting table, of a series of impaling pins, a support behind the table on which said pins are carried, said support movable toward and from the table to project and withdraw said pins to and from position to 60 enter perforations in a work sheet supported on the table, an actuator mounted to slide on the table, means whereby said movement of the actuator is transmitted to the support for moving the latter toward and from the 70 table, a key, and a rack and pinion connecting the key to said actuator for operating the latter.

6. In a typewriting machine, the combination with a platen, of a sheet collating table 75 having a sheet supporting surface on which work sheets may be arranged, impaling pins arranged to project above said surface to enter perforations in the sheets, supports on which said pins are mounted, actuators for 80 said supports; a rock shaft, a key thereon, and operating connections between said rock shaft and said actuators, said supports operable by the actuators to move the impaling pins into and out of sheet holding position. 85

7. In a typewriting machine, the combination with a platen, of a sheet collating table, having a sheet supporting surface on which work sheets may be arranged, impaling pins arranged to project above said surface to enter perforations in the sheets, supports on which said pins are mounted, actuators for 90 said supports; a rock shaft, a key thereon, gears on said shaft, and racks on the actuators driven by said gears. 95

8. In a typewriting machine, the combination with a roller platen and feed rolls to run thereon for advancing work sheets over the platen, of a sheet collating table at the delivery side of the platen on which the 100 leading ends of work sheets may be arranged while said sheets extend around the platen between the latter and the feed rolls, a row of impaling pins extending away from the platen in position to enter perforations in the side margins of the work sheets on the table, and means to simultaneously withdraw said pins in a direction perpendicular to the sheet supporting surface of the table. 105
